FEED WATER DEGASSING APPARATUS

Sergius von Le Juge, Bremen, Germany

Application November 26, 1934, Serial No. 754,930
In Germany November 1, 1934

4 Claims. (Cl. 183—2.5)

In the known feed water degassing apparatus the available heating surface is not always utilized to the best advantage. Furthermore, in the known feed water degassing apparatus special regulating arrangements are required, which, when the apparatus is used on ships, which are never quite steady, do not always operate satisfactorily and are also otherwise undesirable on board ship.

10 Through the invention a feed water degassing apparatus is provided, in which the heating surface is utilized to advantage and in which, even with a fluctuating water supply, the quantity of heating steam is not regulated. The heating steam is therefore no longer throttled as hitherto, when the water supply is small, through the action of a regulator disposed in front of the degassing apparatus, but the heating steam accumulates without regulation in the degassing apparatus, more or less condensation taking place according to the amount of feed water running through.

The invention is illustrated by way of example in section in the accompanying drawing, in which Fig. 1 is a view in vertical section through a diagrammatic representation of the degassing apparatus according to the invention and Fig. 2 a similar view, but only in part section, through another constructional form of the degassing apparatus according to the invention. Referring to the drawing, 1 is a tube through which heating steam is fed to a degassing apparatus 2; 3 is a tube through which the condensate produced from the heating steam is discharged; 4 is a water chamber which is supplied with feed water through a pipe 5; 6 are heating tubes; and 7 is a tank for receiving degassed water.

For conveying the feed water from the chamber 4 into the heating tubes 6 spraying nozzles, for instance in the form of short perforated lengths of tubing 8 which are closed at the bottom are provided, which therefore have small distributing perforations in them and extend with their perforated parts into the heating tubes. The tubes 8 are secured in a bottom tube plate 9 (for example, by being expanded in) which is disposed a short distance above a further bottom tube plate 10, provided for the reception of the heating tubes 6. At their lower ends the heating tubes 6 are in communication with the water collecting tank 7. This connection may be carried out in different ways. In a specially suitable way the heating tubes 6 extend into a basket 11 charged with contact material, which is in communication with the tank 7 through the holes

17 in the side wall of the basket 11. From the steam space of the collecting chamber 7 where the steam from basket 11 collects, a vapour pipe 12 leads to a vapour branch 13 which is secured in the upper tube plate 9.

Through the contact material in the basket the degassing of the water in the tube 6 is improved, that is to say, without the contact material the heating surface (tubes 6) and the quantity of water to be evaporated would have to be greater.

A bottom cover 14 of the basket 11 for the contact material is removable and is for this reason provided with a gland 15.

The diameters of the vapour pipe 12 and of the vapour branch 13 are made such that a space 16 is left between them, the purpose of which will be described hereinafter.

Briefly the degassing apparatus according to the invention operates as follows:

The water to be degassed flows down within the heating tubes 6 being heated by the condensing heating vapour and in part vaporized. The steam flows with the water through the lateral holes 17 in the basket 11 into the collecting tank 7. The steam together with the noxious gases that have been separated out then passes through the vapour tube 12 into the vapour branch 13, no water being carried along by the steam.

In order that air shall not collect in the upper part of the heating tubes 6, the space 18 between the tube plates 9 and 10 communicates with the vapour branch 13 by way of the narrow space 16 formed around tube 12.

To accommodate the apparatus in the feed water circuit it is advantageously placed between the two waste steam pipes (not shown) which are under higher and lower pressures, such pipes being usually provided on board ship. The pipe 1 is thus secured to the waste steam pipe which is under the higher pressure and the vapour branch 13 to the lower pressure. As there is relatively little steam emitted through the vapour branch, the volume of waste steam at low pressure is not unduly increased; it is advantageously condensed as usual in the corresponding low pressure preheater or the jet steam condenser, the gases separated out in the degassing apparatus leaving through the air tube of the low pressure preheater or jet steam condenser.

By the invention the special advantage is attained, that the heating surface is utilized to good purpose and that there is a complete absence of regulating elements which are objected to on board ship for reasons of safety.

If there is no economically useful possibility of condensing the degassing apparatus vapours, the degassing apparatus according to Fig. 2 may be provided with a vapour condenser. This condenser consists of a chamber 19 which is bounded for instance by a tube plate 20, an end 21 and a cylindrical wall 22 which supports the water inflow branch 5. In the plate 20 perforated tubes 23 are secured, through which a portion of the water to be degassed is sprayed into the water chamber 4, where it condenses the vapour. The bulk of the feeding water is supplied to the water chamber 4 through the slotted tubes 24.

This dividing up of the flow of water through the perforated tubes 23 and the slotted tubes 24 has the object of preventing a vacuum being formed, owing to a too great cooling of the vapour, which might interfere with the degassing process.

20 What I claim is:

1. A surface feed water degassing apparatus more particularly for use on board ship, consisting of a casing with a heating steam inlet opening and a condensate outlet opening, upright heating tubes in the casing, a tube plate at the upper ends of the heating tubes for securing the heating tubes, a second tube plate above the first tube plate and at a distance from the latter, spraying nozzles supported by said second tube plate in the upper ends of the heating tubes for conveying the feed water to the inside surfaces of the heating tubes, a vapour opening in the upper tube plate for conveying away the gases between the two tube plates, a water chamber with an inlet opening above the upper tube plate, a water collecting chamber below the casing, a basket containing contact material disposed at the lower end of the heating tubes, the basket being open towards said tubes and having outlets in communication with the water collecting chamber and a vapour pipe in the lower tube plate of smaller diameter than the vapour opening, the vapour pipe leading from the water collecting chamber and opening freely within the vapour opening at a distance from the wall of the vapour opening.

2. A surface feed water degassing apparatus more particularly for use on board ship, consisting of a casing with a heating steam inlet opening and a condensate outlet opening, upright heating tubes in the casing, a tube plate at the upper ends of the heating tubes for securing the heating tubes, a second tube plate above the first tube plate and at a distance from the latter, spraying nozzles supported by said second tube plate in the upper ends of the heating tubes for conveying the feed water to the inside surfaces of the heating tubes, a vapour opening in the upper tube plate for conveying away the gases between the two tube plates, a water chamber with an inlet opening above the upper tube plate, a water collecting chamber below the casing, a basket containing contact material disposed at the lower end of the heating tubes in the interior of the water collecting chamber the basket being open towards said tubes and having outlets in communication with the water collecting chamber and a vapour pipe in the lower tube plate of smaller diameter than the vapour opening, the vapour pipe leading from the water collecting chamber and opening freely within the vapour

opening at a distance from the wall of the vapour opening.

3. A surface feed water degassing apparatus more particularly for use on board ship, consisting of a casing with a heating steam inlet opening and a condensate outlet opening, upright heating tubes in the casing, a tube plate at the upper ends of the heating tubes for securing the heating tubes, a second tube plate above the first tube plate and at a distance from the latter, short perforated lengths of tubing which are closed at the bottom in the upper ends of the heating tubes for conveying the feed water to the inside surfaces of the heating tubes, said short lengths of tubing being supported by said second tube plate, a vapour opening in the upper tube plate for conveying away the gases between the two tube plates, a water chamber above the upper tube plate, a second water chamber with an inlet opening above the first water chamber, a connection between the two water chambers for conveying the water from the upper water chamber partly into the water and partly into the space above the water of the lower chamber, a water collecting chamber below the casing, a basket containing contact material disposed at the lower end of the heating tubes in the interior of the water collecting chamber, perforated side walls for the said basket and a vapour pipe extending through the basket into the water collecting chamber, the said vapour pipe being of smaller diameter than the vapour opening extending from the water collecting chamber and opening freely within the vapour opening at a distance from the wall of the vapour opening. 35

4. A surface feed water degassing apparatus more particularly for use on board ship, consisting of a casing with a heating steam inlet opening and a condensate outlet opening, upright heating tubes in the casing, a tube plate at the upper ends of the heating tubes for securing the heating tubes, a second tube plate above the first tube plate and at a distance from the latter, short perforated lengths of tubing which are closed at the bottom in the upper ends of the heating tubes for conveying the feed water to the inside surfaces of the heating tubes, said short lengths of tubing being supported by said second plate, a vapour branch in the upper tube plate for conveying away the gases between the two tube plates, a water chamber above the upper tube plate, a second water chamber with an inlet opening above the first water chamber, a tube plate between the two water chambers, upwardly extending and downwardly extending tubes in the said tube plate, for conveying the water from the upper water chamber partly into the water and partly into the space above the water of the lower chamber, a water collecting chamber below the casing, a basket containing contact material disposed at the lower end of the heating tubes in the interior of the water collecting chamber, perforated side walls for the said basket and a vapour pipe extending through the basket into the water collecting chamber, the said vapour pipe being of smaller diameter than the vapour opening, extending from the water collecting chamber and opening freely within the vapour opening at a distance from the wall of the vapour opening. 60 65 70
